GAS STOVE

Walter F. Rogers, Oak Park, Ill., assignor to
Crown Stove Works, Cicero, Ill., a corpora-
tion

Original application August 19, 1931, Serial No.
558,015. Divided and this application March
5, 1932. Serial No. 596,974

1 Claim. (Cl. 126—42)

This is a division of application Serial No. 558,-
015, filed August 19, 1931, relating to Gas stoves.

The invention relates to gas stoves of the cab-
inet type in which a door is used for concealing
5 the manifold and valves so that, when the stove
is not in use for cooking purposes, it presents
the appearance of a cabinet or table.

In stoves of this type, the door in front of the
valves must be kept open during the operation of
10 the stove in order to insure an ample supply of
air to the burners and to prevent overheating of
the valves. My Patent No. 1,773,754 issued Au-
gust 26, 1930 covers a structure which was de-
15 signed to prevent closing of this door during the
operation of any one of the burners. In my said
Patent No. 1,773,754, the valves are rotatable on
axes disposed at substantially right angles to the
front wall of the stove and they coact with a
20 valve guard on the inner face of the hinged door
to prevent closing of the hinged door when any
one of the valves is open.

Another type of gas valve which has been in
common use for many years is known as the
25 drop handle valve which has a handle pivoted
on an axis disposed substantially parallel to the
manifold and front wall.

The main objects of this invention are to pro-
vide a gas stove having valves provided with drop
30 handles arranged so as to be adapted to project
through the opening in the front wall of the
stove to prevent closing of the burner box door
when any one of the valves is open.

An illustrative embodiment of this invention is
35 shown in the accompanying drawing, wherein:—
Figure 1 is a fragmentary perspective of a
cabinet gas stove to which this invention is
applied.

Fig. 2 is an enlarged transverse section of the
burner box showing the hinged cover and burner
40 box door in open positions; one of the valve
handles being shown in fully open position pro-
jecting through the front opening of the burner
box.

Fig. 3 is a detail in section, showing one of the
45 gas valve handles in partly open position and ob-
structing the closing of the door.

Inasmuch as this invention is applicable to gas
stoves of many different designs, the accompan-
50 ying drawing illustrates only certain portions of
the stove structure.

In the form shown, the stove comprises a frame
1 having the usual burner top 2, cast metal front
wall 3, and sheet metal walls 4 and 5. A cover
6 is provided for concealing the burner top and
55 also to serve as a table top when the stove is not

used for cooking purposes. This cover is preferably
of the construction disclosed in my Patent No.
1,831,546 issued November 10, 1931. The rear
edge of the cover is connected to the frame by
a hinge 7, so as to permit the cover to be shifted 60
to vertical position to serve as a splasher plate
when the stove is in use.

Located below the burner top, are the usual
gas burners 8 supplied with gas by a manifold 9.
The supply of fuel is controlled by valves 10 65
suspended from the manifold and provided with
handles 11 which are pivoted on a horizontal
axis disposed substantially parallel to the mani-
fold 9 and front wall 3. These valves are ar-
ranged so as to be closed when the handles ex-
70 tend downwardly and to be open when the
handles project forwardly.

Located below the burners, is a drip pan 12
which is slidably mounted on a pair of hori-
zontal rails 13, so as to be adapted to be moved 75
through an opening 14 in the front wall of the
stove. The valve handles 11 are of sufficient
length and are sufficiently close to the front wall
3 so that, when they are open, they project into
the opening 14 of the burner box. 80

Mounted in the opening 14, is a guard or door
15 which is adapted to close said opening for
concealing the manifold, valves, and drip pan.
This door is hinged to the frame by a pair of
screws 16 which are threaded in lugs 17 mounted 85
on the inner face of the door.

Mounted on the inner face of the door adjacent
the lugs 17, is a pair of studs 19 adapted to abut
the rails 13 for securing the door against out-
ward movement beyond the horizontal position 90
shown in Fig. 2. When the door is in its open
position it serves as a guard to prevent the body
and clothes of the operator from coming in con-
tact with the flames during the operation of the
stove. 95

When the valves are only slightly open, the
valve handles may not project forwardly far
enough to resist closing of the burner box door.
For this reason, the inner face of the door is
provided with a transversely disposed rib 20 100
adapted to coact with the valve handles to resist
closing of the door.

When the stove is not in use for cooking pur-
poses, the burner box cover and front door are
closed as shown in Fig. 1. When the stove is 105
in operation, the cover and door are both open
as shown in Fig. 2. When any one of the gas
valves is open, its handle projects forwardly to
serve as a stop for resisting closing of the burner
box door. With this construction, the burners 110

always receive an ample supply of air through the opening 14 during the operation of the stove as fully set forth in my above mentioned Patent No. 1,773,754.

5 I claim:

In a gas range, a range body having a burner top, an upper compartment, a front frame for said compartment, a manifold and valves within

said compartment, handles for said valves movable to beyond the front plane of said compartment, and a safety door hingedly secured to said frame and engageable with the valve handles when they are in open position to prevent the closing of said door.

WALTER F. ROGERS.
